COMBINED PORTABLE TYPEWRITER AND CARRYING CASE

Robert Metzner and Philip H. Stevens, Syracuse, and David O. Chase, Camillus, N.Y., assignors to SCM Corporation, a corporation of New York

Filed Jan. 22, 1962, Ser. No. 68,391

Term of patent 14 years

(Cl. D87—5)

Fig. 4

Fig. 5

FIGURE 1 is a perspective view of a combined typewriter and carrying case in a partially open condition, embodying our new design;

The dominant features of our design reside in the portions shown in full lines.

We claim:

The ornamental design for a combined portable typewriter and carrying case, substantially as shown and described.
